OF MAINE.

WET MACHINE.

1,225,778.

Specification of Letters Patent. Patented May 15, 1917.

Application filed July 19, 1916. Serial No. 116,224.

To all whom it may concern:

Be it known that we, HERVEY G. CRAM and CLIFFORD A. PARSONS, citizens of the United States, residing at Millinocket, in the county of Penobscot, in the State of Maine, have invented an Improvement in Wet Machines, of which the following is a specification.

This invention relates to wet machines, and has reference particularly to means for dividing the layer of pulp on the pulp-receiving roll preparatory to skinning or stripping it from the roll, and to starting the skinning or stripping operation.

In the wet machines, with which the present invention is particularly concerned, the pulp is accumulated upon one, usually the upper of a pair of press rolls, to the desired thickness, being continuously subjected to pressure to eliminate more or less of the water to secure necessary adherence of the mass. Having reached a predetermined thickness, it is desired to remove the pulp layer from the roll, and as such layer is in cylindrical form about the roll, it is required to divide the layer in a direction lengthwise the roll, and then strip it from the roll. Various mechanical devices have been proposed for severing the layer of pulp, though the usual practice is to cut it by a suitable tool controlled by the workman, the operation of which depends upon the dexterity of the workman to secure a proper division. Furthermore, after severance by such methods, it is a matter of some little difficulty to separate the pulp from the surface of the roll, and more particularly to start it for such separation.

One of the objects of the present invention is the provision of pneumatic means, such as an air blast forcibly delivered in the form of numerous closely associated jets, arranged longitudinally of the roll, for automatically dividing the pulp layer on the press roll, substantially longitudinally of the roll, said air blast being directed against the inside of said layer to tear or rupture it on the line of the blast, and when so directed the layer of pulp, adjacent the line of division, will be forced away from the surface of the roll, to start the separation of the layer therefrom, so that the layer may be readily and conveniently detached or removed from the roll and delivered upon a table in sheet form.

Our invention has for another object the association of means with the press-roll or the structural formation thereof, whereby there is provided a narrow unpressed portion in the layer of pulp on said roll, which constitutes a line of weakness, which line extends longitudinally of the roll, at or near the place where the air blast is directed, so that the air blast will rupture the layer of pulp at such line of weakness; and furthermore, if desired, an end-portion of the ruptured layer may be deflected away from the roll to start the skinning or stripping operation.

Figure 1 is a side elevation of a portion of a wet machine having associated with its press-rolls a rupturing and skinning mechanism for the layer of pulp thereon, embodying this invention.

Fig. 2 is a front elevation of the same.

Fig. 3 is a front elevation of the upper press roll which is adapted to receive upon it the layer of pulp and with which the rupturing and skinning mechanism is associated.

Fig. 4 is a longitudinal section of one end-portion of the upper press roll taken on the dotted line 4-4, Fig. 3.

Figs. 5 and 6 are transverse sectional fragments of the upper press roll, taken, respectively, on the dotted line 5-5 and 6-6, Fig. 4.

Figs. 7 and 8 are sectional details illustrating particularly the controlling-valve for the air blast.

Figs. 9, 10, 11, and 12 are enlarged detail views of the actuating-means for the controlling-valve.

The pulp rupturing and skinning mechanism is here shown as applied to or arranged to operate in conjunction with the upper or pulp-receiving roll of the wet machine. This machine comprises essentially a bed or supporting frame 1, from which rise bearings 2, for the lower press roll 3, the bed 1 having vertically projecting frame-bars 4, on which the bearings 5, for the upper press roll 6, are adapted to slide vertically. The bearings of the respective rolls are arranged in vertical alinement, and the bearings for the upper press roll are arranged to receive a continuous downward pressure from suitable springs, not shown, mounted in housings 7 in the frame-bars 4, the tension of which springs may

be adjusted by means, not necessary to describe in detail, but operated by hand wheels 8.

The upper press-roll 6, with which the present invention is here shown as associated, comprises a cylindrical pulp-receiving portion and end-journals. Said press-roll 6, or at least its middle portion which receives upon it the layer of pulp, is made hollow to provide within it a chamber 12, to receive and contain a fluid such as compressed air, which chamber may and preferably will be substantially coextensive with the length of the pulp-receiving portion of the roll, and one of the end journals is made hollow and in open communication with said chamber, by which to conduct compressed air to said chamber.

The pulp-receiving portion of the roll 6 has a recess formed in its outer cylindrical surface, which extends throughout its length, or thereabout, said recess comprising a narrow portion 13, arranged at the bottom of a wider portion 14. The narrow portion 13 is in open communication with the chamber 12, by numerous radially disposed conducting passages 11, so that the compressed air contained in the chamber 12 may pass freely into said narrow recess 13.

A long bar 15, adapted to fit the recess 14, is arranged therein, and rigidly secured in place by bolts 16. The outer face of the bar is curved in continuation of the cylindrical surface of the press roll. Said bar has on its inner side a deep slot or recess 17, extending throughout the length of the recess 14, and the front face of said bar, at the bottom of the slot, is perforated, as at 22, there being here shown two rows of perforations, which rows extend throughout the length of the bar or thereabout. The slot 17 is disposed opposite the recess 13, and is adapted to receive the distributing and controlling-means by which to control the distribution and passage of the compressed air from the recess 13, (which is in open communication with the chamber 12), outward, through the perforations 22. As shown, an air distributing bar 18 is arranged at the bottom of the slot 17, being rigidly secured therein, and said bar is made of a width and length corresponding, respectively, to the width and length of the slot, and its side adjacent the bottom of the slot is cut away or recessed to form a series of elongated chambers 20, which extend over the row or rows of perforations 22, each chamber inclosing several such perforations. Said distributing bar 18 also has conducting passages 19, extended through it, which lead to each chamber, there being at least one such conducting passage for each chamber. These passages 19 are adapted to be valve-controlled, preferably simultaneously, and to accomplish

this result, a valve element 24 is arranged in the slot 17, in slidable engagement with the bar 18, it comprising a body-piece or bar and several transversely disposed valve-plates arranged on the body-piece and separated from each other to correspond with the relative locations of the conducting passages 19. There will be as many of these valve-plates as there are conducting passages 19 in the distributing bar. Said valve-bar is adapted for sliding movement longitudinally in the slot 17, and its valve-plates are adapted for movement with it, to cover and uncover the conducting passages 19. Between the several valve-plates spaces are provided and said spaces are in open communication with the recess 13, and the body-piece of the valve-bar is made narrower than the width of the slot 17, to afford such open communication. Said valve-bar is held pressed into engagement with the air distributing bar by springs 23, arranged in the recess 13, and attached at one end to the bottom of the recess. This valve-element acts as a slide valve, but so far as my invention is concerned, it may be constructed in any suitable manner.

From the above, it is obvious that with the slide valve operated at predetermined moments, air under pressure may be repeatedly conducted from the chamber 12 of the press-roll and caused or permitted to issue as a series of jets through the perforations 22, against the under side of the layer of pulp on the press roll.

On the outer face of the bar 15, above the openings 22, is arranged a long channel or groove 21, extended substantially from end to end of the bar and in parallel relation with the row or rows of perforations 22, said channel being quite narrow, and the layer of pulp, which is formed on the press roll, is extended over said channel, but at or along such portion is not compressed by engagement with the under press-roll, so that over said channel the layer of pulp is quite soft compared with the remaining portion thereof, and thus forms a line of weakness. This weakened line or narrow unpressed portion of the layer is purposely arranged adjacent the perforations 22, so that the issuance of air jets from said perforations and against the under side of the layer of pulp will act to force the layer outward, and tear or rupture it along the line of weakness, and furthermore, one end-portion of the ruptured layer will be deflected in a direction away from the surface of the roll.

Thus it will be observed that when the sliding valve is operated to admit of the air issuing from the perforations, the layer of pulp will be immediately ruptured and one end-portion of the ruptured layer will be forced or blown away from the surface of

the roll, admitting of its being easily stripped from the roll. This stripping will ordinarily proceed automatically. The blast will not only rupture the layer, but blow it outwardly and at the point where gravity will be most effective. The gravity pull of the deflected portion of the pulp and centrifugal force will ordinarily be sufficient to strip the layer of pulp from the roller. Of course, if the stripping by gravity and momentum does not proceed automatically, it may readily be accomplished by hand or other well-known means, but it can be made to operate automatically without difficulty, if reasonable care is used.

To deliver the air under pressure from a suitable source to the chamber 12 of the press-roll, there is secured to one of its journals, a fixed clamping support 29, which receives and holds an end-section of a feed-pipe 30, connected by a pipe with any suitable source of supply. The delivery terminal of the feed pipe 30 is rotatably mounted in what may be termed a slip-joint connection 31, which is carried by the journal of the upper press roll, so that said press roll is free to rotate and also to rise and fall in operation under the accumulated pulp without disturbing the proper non-leaking junction between the air pipe and press-roll.

As heretofore stated, our device is automatic, and means are therefore herein provided by which the accumulation of the pulp to the desired thickness on the press roll and consequent rise of said press roll, will automatically operate the slide-valve 24, to direct the air under pressure to the surface of the roll for the purpose stated. This automatic means, in the preferred embodiment, as here shown, will now be described.

A cylinder 32 is secured to one end of the press-roll at one side of the center and in line with the slide-valve 24, see Figs. 4 and 7, said cylinder has a piston-chamber which contains a piston 38, which is operatively connected with the slide valve 24, by a stem 39, extended through a stuffing-box 40, and movement of the piston in the cylinder acts to correspondingly move the slide-valve. Compressed air from the chamber 12 of the hollow press-roll is adapted to be delivered to said cylinder by which to control the movement of the piston; and the delivery of air to the cylinder is controlled by a valve adapted for operation by means controlled by the rising press-roll.

As here shown, a pipe connection 33 leads from the chamber 12, to the outer end-portion of the cylinder 32, and in said end-portion there are arranged suitable ports which are controlled by the controlling-valve 41. 26 represents a port connected with the pipe-connection 33, which may be angularly formed and leads to the valve-chamber of the controlling-valve 41. 37 represents a

port leading from the valve-chamber to one end of the piston-chamber of the cylinder 32. 36 represents a port leading from the valve-chamber to the other end of the piston-chamber of the cylinder 32. 46 represents a port leading from the valve-chamber to the atmosphere, which serves as the exhaust-port.

The controlling valve 41 is made as a rotary disk which is arranged in the valve-chamber against a flat seat which forms the bottom wall of the chamber, and all of said ports terminate at said seat so that said disk-valve may control all of said ports. The contact-face of said disk-valve has curved channels, see dotted lines Fig. 8, for inter-communication between the several ports in such manner that when the valve is in one position an open way is established between the chamber 12 and port 37, leading to one end of the cylinder, and when in such position the port 36 leading to the other end of the cylinder is in open communication with the exhaust-port 46; and when in another position an open way is established between the chamber 12 and the port 36 leading to the other end of the cylinder, and when in such position open communication is established between the port 37 and the exhaust-port 46. Such construction admits of the employment of a disk-valve adapted for complete and continuous rotation and for the longitudinal reciprocation of the piston and consequent corresponding movement of the sliding-valve 24.

It is, therefore, apparent that by proper control of the valve 41, the air may be admitted to the cylinder with a view to positioning the sliding-valve so as to permit the compressed air to pass through the perforations of the roll, or with a view to so operating said sliding-valve as to cut off said air supply.

The automatic operation of the controlling valve 41 is directly controlled by the upper press-roll, the direct actuation of said valve being governed by an operating-wheel 51, connected to the stem 48 of said valve, said wheel having two pairs of diametrically opposed radial arms, one pair of which, as 52, are made narrower than the other pair 53, the narrow arms being utilized to operate the wheel, and move the disk-valve rotarilly, for admitting air to the cylinder to operate the sliding-valve and control the delivery of air to the surface of the cylinder, and the wider arms being utilized to operate the wheel to move the disk-valve rotarilly to shut off the air. Said wheel is adapted for intermittent operation in the same direction of rotation, and being arranged on the press-roll as shown is adapted to revolve about the axis of said roll.

For operating the operating-wheel 51, there is secured to the movable bearing of

the upper press-roll a support 54, see Fig. 1, the lower end of which is laterally deflected, at 55, and terminates in an elongated guide or bearing 56. A rod 57 is movably mounted in said guide to slide longitudinally, and is disposed at right angles to the plane of the operating wheel 51. That end of the slide rod 57 next said wheel has a pin 58, which, as the rod is moved in one direction, as for instance to the left, see Fig. 12, enters the orbital path of the arms of the operating-wheel, to be engaged by one of the arms thereof, and thereby cause a quarter turn of said wheel, and as the rod is moved in the other direction, as for instance to the right, see Fig. 10, is removed from the orbital path of the operating-wheel, so that said wheel will pass by it freely.

Secured to a fixed part of the frame, as for example, the support for a shelf which may be arranged to receive the layer of pulp from the roll, is a trunnion 59, on which is rotatably mounted a sleeve or hub 60, having a radial arm 61, which extends through a slot in the guide-bearing 56, and through a slot 62 in the slide-rod 57, the slots permitting necessary movement of the arm to reciprocate the slide-rod without interference, and to hold the arm against other than swinging movements with relation to the slide-rod. The sleeve 60 also has a lateral extension 63, the terminal of which is connected to the guide 56 by an adjustable connecting rod 64, loosely connected at its remote ends, respectively, to the guide or bearing 56, and to the extension 63. Said rod may be composed of two parts adjustably connected by a coupling 65. As the movable bearing for the press-roll rises and falls, the support 54 is correspondingly moved and through the connecting rod the sleeve 60 is rocked and the arm 61 moved to move the slide-rod 57 toward the operating wheel 51, and the pin 58 thereon into the path of the arms thereof. Said wheel is adjusted on the valve-stem in such position that one of the narrow arms thereof engages the pin 58 of the slide-rod, when the slide-rod has been moved sufficiently by the arm 61, that is, when the layer of pulp has accumulated on the roll to a predetermined thickness. This engagement, on continued rotation of the press-roll turns the operating wheel 51 approximately 90 degrees, and correspondingly turns the disk-valve and controls the piston, as previously described to cause delivery of the air blast. Further rotation of the press-roll carries the operating wheel 51 past the pin 58 and to a position to cause the adjacent wide arm 53 thereof to engage a lug 66, fixed to the support 54, by which said wheel is rotated in the same direction approximately another 90 degrees, thereby to reverse the position of the disk-valve passages, and shut off the air blast. This resets the

operating-wheel for further operation by the slide-rod. Rotation of the press-roll therefore may be continuous. The lug 66 is so arranged that it is beyond the path of the narrow arms. The projection 58 on the slide-rod is obviously controlled by the rise of the press-roll, that is, the thickness of the layer of pulp thereon, through the connection 64, and as this connection is adjustable, the slide-rod may be arranged for movement to a wheel-engaging position, at any desired rise of the press-roll, that is, at any predetermined thickness of the layer of pulp on such roll.

We have referred to the use of compressed air for dividing the layer, but obviously other fluids may be used with equivalent results.

We claim:—

1. A wet machine comprising a pair of co-operating press-rolls arranged to compress a layer of pulp on the pulp-receiving roll during the formation thereon, and having means associated therewith for forming a line of weakness longitudinally thereof, and pneumatic-means arranged to rupture said layer at said line of weakness.

2. A wet machine comprising a pair of co-operating press-rolls arranged to compress a layer of pulp on the pulp-receiving roll and to leave a narrow unpressed weakened line longitudinally thereof and pneumatic-means arranged to rupture the layer of pulp at said weakened line.

3. A wet machine comprising a pair of co-operating press-rolls arranged to compress a layer of pulp on the pulp-receiving roll and to leave a narrow unpressed weakened line longitudinally thereof and pneumatic-means arranged to rupture the layer of pulp at said weakened line, and to deflect the end-portion of the ruptured layer away from the roll.

4. A wet machine comprising a pair of co-operating press-rolls arranged to compress a layer of pulp on the pulp-receiving roll and to leave a narrow unpressed weakened line longitudinally thereof, and pneumatic-means arranged to deliver a current of air against the inner side of the layer of pulp on said roll at the unpressed weakened portion thereof to rupture the pulp layer entirely across the same.

5. A wet machine comprising a pair of co-operating press-rolls arranged to compress a layer of pulp on the pulp-receiving roll and to leave a narrow unpressed weakened line longitudinally thereof, and pneumatic-means arranged to deliver a current of air against the inner side of the layer of pulp on said roll adjacent the unpressed weakened portion thereof to rupture the same, and to deflect the end-portion of the ruptured layer away from the roll.

6. A wet machine comprising press-rolls, on one of which the pulp is accumulated in

the operation of the machine, one of said rolls being formed to provide a narrow unpressed portion in the layer of pulp, during the operation of the rolls, and pneumatic-means arranged to rupture the layer of pulp at said unpressed portion.

7. A wet machine comprising press-rolls, on one of which the pulp is accumulated in the operation of the machine, one of said rolls being formed to provide a narrow unpressed portion in the layer of pulp, during the operation of the rolls, and pneumatic-means arranged to rupture the layer of pulp at said unpressed portion, and to deflect the end-portion of said layer in a direction away from the roll.

8. A wet machine comprising press-rolls, the pulp-receiving roll having a slot to provide an unpressed weakened line in the layer of pulp during its formation on the roll and pneumatic-means arranged to rupture said layer at its weakened line.

9. A wet machine comprising press-rolls, the pulp-receiving roll having a slot to provide an unpressed weakened line in the layer of pulp during its formation on the roll and pneumatic-means arranged to rupture said layer at its weakened line, and to deflect the end-portion of the ruptured layer away from the roll.

10. A wet machine comprising press-rolls, on one of which the pulp is accumulated in the operation of the machine, one of said rolls being formed to provide a narrow unpressed portion in the layer of pulp during the operation of the rolls, and pneumatic-means arranged to deliver a current of air against the inner side of the layer of pulp on said roll adjacent the weakened portion thereof to rupture the same at the weakened portion.

11. A wet machine comprising press-rolls, on one of which the pulp is accumulated in the operation of the machine, one of said rolls being formed to provide a narrow unpressed portion in the layer of pulp during the operation of the rolls, and pneumatic-means arranged to deliver a current of air against the inner side of the layer of pulp on said roll adjacent the weakened portion thereof to rupture the same at the weakened portion, and to deflect the end-portion of the layer away from the roll to start the skinning operation.

12. In a wet machine, a pulp-receiving roll upon which a layer of pulp is formed, said roll having a longitudinal recess, a bar arranged in the recess, having perforations extended to the outer surface of the roll, and having an exterior channel arranged adjacent said perforations and in parallel relation therewith.

13. In a wet machine, a hollow pulp-receiving roll adapted to contain compressed air, and means arranged to deliver the com-

pressed air from the interior of said roll through perforations arranged at the exterior surface thereof, against the inner side of the layer of pulp on the roll, and means associated with said roll for forming a line of weakness in the layer of pulp adjacent the perforations, whereby the air forcibly issuing from the perforations will act to rupture the layer entirely across the same at the line of weakness, and to deflect a ruptured end-portion away from the roll.

14. A wet machine comprising a pair of coöperating press-rolls arranged to compress a layer of pulp on the pulp-receiving roll and to leave a narrow unpressed weakened line longitudinally thereof and pneumatic-means arranged to rupture the layer of pulp at said weakened line, including a valve adapted to control said means.

15. A wet machine comprising press-rolls, on one of which the pulp is accumulated in the operation of the machine, one of said rolls being formed to provide a narrow unpressed portion in the layer of pulp during the operation of the rolls, and pneumatic-means arranged to deliver a current of air against the inner side of the layer of pulp, throughout its width, and adjacent the weakened portion thereof, to rupture the same at the weakened portion, said pneumatic-means including a controlling-valve.

16. A wet machine comprising press-rolls, on one of which the pulp is accumulated in the operation of the machine, one of said rolls being formed to provide a narrow unpressed portion in the layer of pulp during the operation of the rolls, and pneumatic-means arranged to deliver a current of air against the inner side of the layer of pulp, throughout its width, and adjacent the weakened portion thereof to rupture the same at the weakened portion, including a valve arranged in the roll and slideable longitudinally to control the delivery of air.

17. In a wet machine, a hollow pulp-receiving roll adapted to contain compressed air, and means arranged to deliver the compressed air from the interior of said roll through perforations arranged at the exterior surface thereof, against the inner side of the layer of pulp on the roll, and means associated with said roll for forming a line of weakness in the layer of pulp adjacent the perforations, whereby the air, forcibly issuing from the perforations, will act to rupture the layer at the line of weakness, and deflect a ruptured end-portion away from the roll, and a valve coextensive with the perforations for controlling the passage of air therethrough.

18. In a wet machine, a pulp-receiving roll upon which a layer of pulp is formed, said roll having a longitudinal recess, a bar arranged in the recess having perforations extended to the exterior surface thereof, an

- air-distributing member extended over the inner side of said perforated bar, having air chambers inclosing groups of perforations and having air passages leading to the several chambers, and a slidable valve member arranged on said distributing-member for controlling the delivery of air through said air passages, and means for reciprocating said valve-member.
19. In a wet machine, a pulp-receiving roll upon which a layer of pulp is formed, said roll having a longitudinal recess, a recessed bar arranged in the recess of the roll having perforations extended from the recess in the bar to the exterior surface thereof, an air-distributing member arranged in the recess in the bar over said perforations, having air chambers inclosing said perforations and having air passages leading to said chambers, a sliding valve member arranged on said distributing member and controlling said air passages, and means for operating said valve-member.
20. A wet machine comprising a pair of coöperating press-rolls arranged to compress a layer of pulp on the pulp-receiving roll of the pair and to form a narrow weakened portion longitudinally of the roll, and pneumatic-means arranged to rupture the layer of pulp at said weakened line, including a controlling valve for said means adapted for automatic operation.
21. A wet machine comprising a pair of coöperating press-rolls arranged to compress a layer of pulp on the pulp-receiving roll of the pair and to leave a narrow unpressed portion longitudinally thereof, and pneumatic-means arranged to direct a blast of air against the inner side of said layer adjacent said unpressed portion to rupture the layer of pulp along said unpressed portion, said pneumatic-means including a controlling-valve for the delivery of the air blast adapted for automatic operation.
22. A wet machine comprising a pair of coöperating press-rolls arranged to compress a layer of pulp on the pulp-receiving roll of the pair and to form a weakened portion longitudinally of the roll, and pneumatic-means arranged to rupture the layer of pulp along said weakened portion including a controlling-valve, and means operated by the rise of the press-roll to govern the operation of said controlling-valve.
23. A wet machine comprising a pair of coöperating press-rolls arranged to compress a layer of pulp on the pulp-receiving roll of the pair and to form a weakened portion longitudinally of the roll, and pneumatic-means arranged to rupture the layer of pulp along said weakened portion including a piston-actuated controlling-valve, and means to control the movement of the piston, adapted for operation by the rise of the press-roll.
24. A wet machine comprising a pair of coöperating press-rolls arranged to compress a layer of pulp on the pulp-receiving roll of the pair and to form a weakened portion longitudinally of the roll, and pneumatic means arranged to rupture the layer of pulp along said weakened portion including a piston-actuated controlling-valve, a pipe connection between the cylinder containing the piston and the chamber of the press-roll, a valve governing the passage of air through said pipe-connection adapted for operation by the rise of the press-roll. 70
25. A wet machine comprising a pair of coöperating press-rolls arranged to compress a layer of pulp on the pulp-receiving roll of the pair and to form a weakened portion longitudinally of the roll, and pneumatic-means arranged to rupture the layer of paper along said weakened portion, and means to control said pneumatic-means having an operating-member, actuating-means for said operating-member, and means controlled by the rise of the press-roll for moving the actuating-means into and out of coaction with the operating-member. 75
26. A wet machine comprising a pair of coöperating press-rolls arranged to compress a layer of pulp on the pulp-receiving roll of the pair and to form a weakened portion longitudinally of the roll, and pneumatic-means arranged on the press-roll for rupturing the layer of pulp along said weakened portion, controlling-means arranged on the press-roll for said pneumatic-means, 80 having an operating-member, and actuating-means for the controlling-means arranged for movement upon the rise of the press-roll, into and out of coactive position. 85
27. A wet machine comprising a pair of coöperative press-rolls arranged to compress a layer of pulp on the pulp-receiving roll of the pair, pneumatic-means arranged to rupture said layer of pulp entirely across the same, and controlling-means for said pneumatic-means adapted for operation upon a rising movement of the press-roll and during rotation thereof. 90
28. A wet machine comprising a pair of coöperative press-rolls arranged to compress a layer of pulp on the pulp-receiving roll of the pair, pneumatic-means arranged to rupture said layer of pulp entirely across the same, having a controlling-element arranged on the press-roll, and an actuator 100 therefor having an operating-element arranged on the press-roll, and means to actuate said operating-element which is separately supported but adapted for coaction with the operating-element upon a rising movement of the press-roll and during its rotation. 115
29. A wet machine comprising a pair of coöperative press-rolls arranged to compress a layer of pulp on the pulp-receiving roll 120

of the pair, pneumatic-means arranged to rupture said layer of pulp entirely across the same, having a controlling-element arranged on the press-roll, an actuator therefor having an operating-element arranged on the press-roll, and means to actuate said operating-element which is separately supported but adapted for successive coaction with the operating-element upon a rising movement of the press-roll and during its rotation, to open and close the pneumatic-means.

30. A wet machine comprising a pair of coöperative press-rolls arranged to compress a layer of pulp on the pulp-receiving roll of the pair, pneumatic-means arranged to rupture said layer entirely across the same, a pulp-controlling means for said pneumatic-means, including a rotatable operating-member arranged on the press-roll and adapted to move in an orbital path, and means moved by the rising press-roll into the orbital path of said operating-member to cause rotation of said member as the press-roll rotates to open the pneumatic-means.

31. A wet machine comprising a pair of coöperative press-rolls arranged to compress a layer of pulp on the pulp-receiving roll of the pair, pneumatic-means arranged to rupture said layer entirely across the same, a pulp-controlling means for said pneumatic-means, including a rotatable operating-member arranged on the press-roll and adapted to move in an orbital path, and means moved by the rising press-roll into the orbital path of said operating-member to cause rotation of said member as the press-roll rotates to open the pneumatic-means, and means also arranged in the orbital path of the operating-member beyond the aforesaid means and adapted to be engaged by the operating-member as the press-roll rotates to close the pneumatic-means.

32. A wet machine, comprising a pulp receiving roll and a coöperating press-roll to press a layer of pulp on the pulp-receiving roll during the operation thereof, an opening or openings on the surface of the pulp-receiving roll, extending across the same, means to forcibly project air outwardly through said opening or openings against the inside of the layer of pulp, with sufficient power to rupture the layer of pulp entirely across the same.

33. A wet machine comprising a pulp receiving roll and a coöperating press-roll to press a layer of pulp on the pulp-receiving roll during the operation thereof, an opening or openings on the surface of the pulp-receiving roll, extending across the same, means to forcibly project air outwardly through said opening or openings against the inside of the layer of pulp, with sufficient power to rupture the layer of pulp entirely across the same, and to deflect the

end-portion of the ruptured layer away from the roll.

34. A wet machine comprising a pulp receiving roll and a coöperating press-roll to press a layer of pulp on the pulp-receiving roll during the operation thereof, an opening or openings on the surface of the pulp-receiving roll, extending across the same, means to forcibly project air outwardly through said opening or openings against the inside of the layer of pulp, with sufficient power to rupture the layer of pulp entirely across the same, and a valve to control said means.

35. A wet machine comprising a pulp receiving roll and a coöperating press-roll to press a layer of pulp on the pulp-receiving roll during the operation thereof, an opening or openings on the surface of the pulp-receiving roll, extending across the same, means to forcibly project air outwardly through said opening or openings against the inside of the layer of pulp, with sufficient power to rupture the layer of pulp entirely across the same, and a controlling valve for said pneumatic means adapted for automatic operation.

36. A wet machine comprising a pulp receiving roll and a coöperating press-roll to press a layer of pulp on the pulp-receiving roll during the operation thereof, an opening or openings on the surface of the pulp-receiving roll, extending across the same, means to forcibly project air outwardly through said opening or openings against the inside of the layer of pulp, with sufficient power to rupture the layer of pulp entirely across the same, including a controlling-valve for said pneumatic means adapted for operation by the rise of the press-roll.

37. In a wet machine, a pulp receiving roll and a coöperating press-roll arranged to compress a layer of pulp on the pulp-receiving roll during the operation thereof, having associated therewith means to predetermine the line of rupture across said layer, and means arranged to rupture said layer at such predetermined line and to deflect the end-portion of the ruptured layer to facilitate its removal from the roll.

38. In a wet machine, a pulp receiving roll and a coöperating press-roll arranged to compress a layer of pulp on the pulp-receiving roll during the operation thereof, having associated therewith means to predetermine the line of rupture across said layer, and pneumatic means arranged to forcibly project air to rupture said layer at such predetermined line, and to deflect the end-portion of the ruptured layer to facilitate its removal from the roll.

39. A wet machine, comprising a pulp receiving roll and a coöperating press roll to press a layer of pulp on the pulp-receiving roll during the rotation thereof, an

opening or openings on the surface of the pulp-receiving roll, extending across the same, means to forcibly project air outwardly through said opening or openings 5 against the inside of the layer of pulp, with sufficient power to rupture the layer of pulp entirely across the same and deflect it outwardly when the layer has reached a predetermined thickness and when the openings 10 and the axis of the receiving roll are in an approximately horizontal plane, whereby

the layer of pulp will be stripped from the roll by gravity and centrifugal force.

In testimony whereof, we have signed our names to this specification, in the presence 15 of two subscribing witnesses.
